Inventor:
Charles Kolin

By Rummel & Rummel
Attn: Attn:

UNITED STATES PATENT OFFICE.

CHARLES KOLIN, OF ROCHELLE, ILLINOIS.

DRY-CLEANING APPARATUS.

1,359,178.

Specification of Letters Patent. Patented Nov. 16, 1920.

Application filed June 28, 1920. Serial No. 392,504.

To all whom it may concern:

Be it known that I, CHARLES KOLIN, a citizen of the United States of America, and a resident of Rochelle, county of Ogle, State 5 of Illinois, have invented certain new and useful Improvements in Dry-Cleaning Apparatus, of which the following is a specification.

The purposes of this invention are to 0 provide a convenient device for the use of garment cleaners in employing cleaning fluids such as gasolene, alcohol, ammonia, etc., or mixtures of such fluids. Another purpose of the invention is to provide in 5 such a cleaning apparatus means for warming the cleaning fluid by some such simple means as a container for hot water which the cleaning pan proper surmounts. The advantage of warming the cleaning fluid 0 is that its action is better than at normal temperature, and further that cleaning fluids commonly employed are less injurious to the hands of the workman if warmed somewhat above normal temperature.

5 The objects of the invention are accomplished by the device shown in the accompanying drawings, in which—

Figure 1 is a perspective view of a cleaning apparatus constructed according to this 0 invention.

Fig. 2 is a longitudinal sectional view.

Fig. 3 is a transverse section taken on line 3—3 of Fig. 2.

The general arrangement of the design is 5 a sheet metal receptacle having a lower compartment for hot water with a suitable inlet and drain, and an upper compartment, the floor of which forms a suitable surface for supporting garments during the 0 cleaning operation, and is inclined toward a depressed part of the floor to receive sediment. Valve controlled drainage means communicates with the sediment collector. The upper compartment supports above the 5 liquid level, a drainage basket for receiving the cleaned garments.

Referring to the drawings, there is shown a rectangular sheet metal cleaning pan; 1, separated into two compartments 2 and 3 by the partition 4 forming an inclined floor for compartment 2 and a top for compartment 3. Compartment 3 is filled with hot water either by connections to a hot water

system or a suitable means by which the hot water may be poured into compartment 3. 55 The drawings show an inlet to this compartment controlled by a valve 5, and an outlet controlled by a valve 6. Compartment 2 is open at its top and supports a drainage basket 7, in which the cleaned garments 60 are placed so that the cleaning fluid held by the garments may drain back into the compartment 2. 8 indicates the cleaning fluid, and 9 is a depression at the lower end of floor 4 in which sediment collects. This 65 depression is inclined from side to side of the apparatus and at its lower end is provided with a valve controlled drain 10. The pocket formed by the depression 9 is normally covered by a removable screen. 70

In the operation of the device, the cleaning fluid being warmed by the hot water in compartment 3 has a better action than when at normal temperature and is also less injurious to the hands of the workman. 75 The garment to be cleaned is laid on the floor 4 and brushed as usual, the dirt removed settling through the perforated cover 11 into the pocket 9. The sediment may be drained from the compartment 2 at desired intervals. The basket 7 forms a convenient means for receiving the cleaned garments permitting the cleaning fluid to drip therefrom into compartment 2. 80

I claim:

1. A dry cleaning apparatus consisting of an open pan relatively long and shallow, having the bottom inclined longitudinally at a slight angle and having a settling and sediment pocket in the lower end, the 90 pocket having a strainer cover substantially flush with the bottom of the pan and a reticulated receptacle mounted within the pan at the upper part thereof, for draining off liquid from the cleaned garments. 95

2. A dry cleaning apparatus comprising an open pan for a cleaning fluid, the pan having a floor, which is inclined toward one end, said floor having a depression at its lower end, and an outlet for said depression. 100

3. A dry cleaning apparatus consisting of an open pan for a cleaning fluid, surmounting a closed container for a heating fluid, said closed container having an opening for an inlet in the front side of the higher part 105 and a drain in the end of the floor.

4. A dry cleaning apparatus comprising an open pan surmounting a container for the heating fluid, said pan having a floor which is inclined toward one end and a strainer at the lower end of said floor.

5. A dry cleaning apparatus comprising an open pan for a cleaning fluid, surmounting a container for a heating fluid, the pan having a floor which is inclined toward one end, said floor having a depression at its

lower end, and a strainer covering said depression.

6. A dry cleaning apparatus comprising an open pan for a cleaning fluid, surmounting a container for a heating fluid, and a ¹⁵ foraminous basket supported by said pan.

Signed at Chicago this 21st day of June, 1920.

CHARLES KOLIN.
